VAPOR GENERATOR

Charles S. Smith, Westfield, N.J., assignor to The Babcock & Wilcox Company, New York, N.Y., a corporation of New Jersey

Filed Oct. 25, 1957, Ser. No. 692,302

7 Claims. (Cl. 122—478)

This invention relates generally to a vapor generator including means for highly superheating the vapor produced therein. More particularly the invention is concerned with a novel arrangement and construction of a vapor or steam superheater and reheat and their relationship to each other and to other components of the steam generator for producing superheated steam at substantially constant high temperature under conditions which involve widely varying generator loads.

As the theoretical amount of work obtained from superheated steam supplied to an associated prime mover is determined by the differential in the total heat content of the steam between the entering and leaving conditions thereof, it has been recognized that sustained high thermal efficiency of the prime mover is dependent both on high initial steam temperature and the maintenance of this temperature over a considerable extent of the load range. The working fluid or high temperature steam supplied to such prime movers is generally produced as a result of radiant absorption by a steam generator furnace wall tubes of heat given up by products of combustion within the furnace; the steam generated thereby being separated from the saturated water combined therewith as it issues from the wall tubes and the separated steam subsequently being superheated to a temperature in the order of 1050° F. or higher. Oftentimes economy dictates that steam which had been expanded in a prime mover be also reheated to substantially the initial superheat temperature and thereafter returned to the prime mover or turbine.

To attain superheat steam temperatures of the order required, it is sometimes necessary to position a portion of the superheater so as it will be exposed to furnace radiation. However, this involves certain difficulties with reference to heat transfer rates and superheater metal temperatures. These difficulties are particularly aggravated in furnaces fired by slag forming fuels operating at temperatures above the fusion temperatures of the incombustible particles in such fuels, since these particles at elevated temperatures tend to remain in a molten sticky condition which causes them to adhere to the radiant heat absorbing surfaces of the superheater and accumulate thereon.

An object of this invention is to effectively obtain high superheat temperatures by uniquely positioning a portion of the vapor superheating surfaces in a high temperature zone of a furnace in such a manner as to minimize attenuating slagging tendencies and excessive superheater tube metal temperatures.

Another object of the invention is to provide a novel superheater arrangement whereby the desired high superheat steam temperature is maintained substantially constant throughout widely varying load conditions.

These and other allied objects and advantages are obtained in a steam generator arrangement which generally comprises a water cooled furnace section having a connected associated gas pass in communication with a steam cooled convection section. A plurality of vertically spaced

2

burner means firing a slag forming fuel discharges hot gaseous products of combustion at above ash fusion temperatures into the lower portion of the furnace chamber. These gases flow upwardly through the furnace and thence serially through the connected gas pass and the associated convection section. Steam generated in the walls of the furnace chamber is then separated from the saturated residual water issuing from the furnace wall tubes in a separating drum positioned above the furnace.

10 According to this invention the saturated steam upon leaving the separating drum passes first through the wall tubes of the convection section where it becomes slightly superheated. This slightly superheated or dry steam then passes through a radiant section of a primary superheater disposed in the high temperature zone of the furnace which is exposed to the radiant heat of the products of combustion flowing upwardly through the furnace. Steam superheated in this radiant section is then serially passed to a convection section of a primary superheater located in the relatively low gas temperature zone within the convection section where the steam is heated to an intermediate temperature. The intermediate heated steam is then finally heated by flowing the same through a secondary superheater disposed in the gas pass which is adjacent the gas exit of the furnace. Reheating of steam which has passed through a prime mover is provided for by positioning a reheat for receiving the same between the radiant primary section of the superheater and the secondary superheater in the vicinity of the furnace exit and the gas pass entrance.

According to this invention slag accumulation on the radiant superheater surfaces is minimized by flowing relatively cool steam therethrough and by arranging the superheating surfaces as depending, vertically extending, tube platens which comprise a plurality of return bend tubes in which the laterally extending tube portions at the bends is provided with a minimum radius. With this platen arrangement a minimum plane of radiant superheater surface is exposed transversely of the gas flow, the transversely extending surfaces being the surfaces upon which the major portion of the slag generally tends to accumulate thereon due to the direct impingement of the entrained slag particles in the gas flow.

According to this invention superheat and reheat control under widely varying load conditions is attained by burner selection and manipulation and by regulably controlling the amount of gas flow over the convection section of the superheater, the latter being accomplished by a damper controlled bypass in the convection section.

50 A feature of this invention resides in the provision of initially flowing relatively cool, dry steam through radiant primary heat absorbing tubes exposed to the high temperature gases in the furnace.

Another feature of this invention resides in the positioning of reheat surfaces physically and gas flow wise in a zone between the radiant superheater and the secondary superheater in a generating unit of a type as herein described.

Still another feature of this invention resides in the provision of a novel organization and construction of radiant superheating surfaces arranged to minimize accumulations of slag thereon and for maintaining the metal temperatures thereof within tolerable limits.

Other features and advantages will be readily apparent when considered in view of the drawings and the descriptions thereof in which:

Fig. 1 is a diagrammatic vertical section view of a vapor generating and superheating unit according to this invention.

70 Fig. 2 is a half plan section taken along line 2—2 of Fig. 1.

Fig. 3 is a detailed side view of a radiant superheater arrangement according to this invention.

Fig. 4 is a front view of a radiant superheater arrangement of Fig. 3.

Fig. 5 is a section view taken along line 5—5 of Fig. 3.

The illustrated vapor generating and superheater unit comprises a steam generator intended for central station use having a generating capacity of approximately 1,700,000 lbs. of steam per hr. with a total steam temperature at the superheater outlet in the order of 1050° F. at 2425 lbs. p.s.i. Included also is a steam reheater for obtaining a reheat steam temperature substantially of the same order as the high pressure steam temperature.

Referring to Fig. 1, the unit comprises an elongated furnace chamber 10 having a laterally extending gas pass 11 adjacent the upper end thereof and a downwardly extending convection section 12 connected thereto. The furnace 10 is preferably of rectangular cross-section defined by walls 13, 14 and 15 of steam generating tubes. The front wall 13 includes a row of tubes 16 extending upwardly from a water supply drum 17 to an upper front wall header 18; the rear wall 15 includes a row of tubes 19 extending from water supply drum 20 to upper rear wall header 21, the lower portions of the tubes 16 and 19 in the front and rear wall being inwardly and downwardly inclined to form a hopper bottom 22 terminating in a slag opening 23. The side walls 14 each include a row of tubes 24 extending between lower wall headers 25, 26, 27 and upper side wall header 28. Upper headers 18, 21 and 28 in turn are connected to a steam and water separating drum 29 by suitable conduits 30, 31 and 32 respectively, through which steam generated in the furnace walls and residual water mixed therewith is discharged into the steam drum 29.

A portion of the rear wall tubes 19A immediately below the laterally disposed furnace gas exit 33 are inwardly bent to form a nose arch 34 in which the upper inclined portion 34A of the arch in effect constitutes an extension of the horizontally extending gas pass floor 35. Above the arch the tube portions 19A extend vertically upward, connecting into header 21. These tube extensions together with the vertically extending tube portions 19 of the rear wall form a screen 36 disposed as spaced platens (see Fig. 2) to provide openings therebetween for the passage of the gas from the furnace 10 to the lateral gas pass 11. A portion of the side wall tubes 24A in the vicinity of the arch 34 extend laterally and connect into a header 37 from which extend vertical tubes 38 to line the side walls of the gas pass 11.

The generating unit shown is of the natural circulating type with feed water being supplied to the upper drum 29. Downcomers 39 and 40 interconnect drum 29 with the lower supply drums 17 and 20 to supply the wall tubes 16, 19. The lower side wall headers 25, 26 and 27 and associated wall tubes 24 are also supplied from drums 17 and 20 by suitable conduits not shown.

Suitable burners 41 for firing the unit are vertically disposed in the lower portion of the front wall 13. The hot gaseous products of combustion therefrom pass upwardly through the furnace chamber 10, thence through the lateral gas pass 11 and finally downward through the convection section 12.

According to this invention the peripheral walls 14A, 42 and 43 of the convection section 12 form a "bird cage" i.e. are lined with steam cooling tubes. Saturated steam is delivered from the steam drum 29 through steam conduits 44 to a distributing header 45 disposed above and adjacent the gas exit 46 of the lateral gas pass 11. A row 47 of steam cooled tubes line wall 42 of the convection pass and connects the distributing header 45 to a ring header 48 disposed adjacent the bottom of the convection pass 12. A second row 49 of steam tubes, extending from header 45 and along the roof 50 and opposite wall 43 of the convection pass, connects into an opposite leg 48A of the ring header 48. Dividing the

convection pass 12 into a main gas pass 51 and a gas by-pass 52 is a third row 53 of steam tubes, spaced from wall tubes 47 and extending from the distributing header 45 to the ring header 48. The convection section side wall tubes 54 connect the ring header 48 to upper convection pass side wall headers 55, the steam going from the distributing header 45 down through tube rows 47, 49 and 53 to the ring header 48 and discharges therefrom into the side wall tube rows 54.

A metallic wall 56 constituting an extension of the division wall tube row 53, divides the lower portion of the convection section 12 and terminates at dampers 57 and 58 which proportion the gases flowing through the respective gas passes as will be hereinafter described.

Steam from the side wall headers 55 is delivered through conduit 59 to a header 60 disposed below the floor 35 of the gas pass 11. A row 61 of tubes connected into header 60 extend upwardly and rearwardly along the gas pass floor 35. Adjacent the exit of the gas pass, the floor tubes 61 extend vertically, and together with the upper portion of tube row 47, form a screen 62 across the exit 46 of the gas pass. Continuation of tubes 61 are extended along the furnace roof 63 and connect with the overheating tube banks.

According to this invention the superheating portion or tube banks of the unit comprises a radiant primary superheater section 64 disposed in the upper forward zone of high temperature of the furnace, a second portion 65 of the primary superheater disposed in the relatively cool temperature zone of the main gas pass 51 of the convection section and a secondary superheater 66 including a bank of tubes vertically disposed in the intermediate temperature zone of the lateral gas pass between the screens 36 and 62.

Referring to Figs. 1 to 4 the radiant superheater 64 comprises a plurality of relatively wide spaced tube banks or platens 67 transversing the width of the furnace. Each platen 67 includes an inlet header 68 positioned adjacent the front wall 13 and normal thereto and an outlet header 68A spaced therefrom and in alignment therewith. Spaced from and substantially co-extensive with the aligned inlet and outlet headers 68, 68A is an intermediate header 69. Connecting the inlet and outlet headers 68, 68A to the intermediate header 69 are a plurality of depending return bend tubes 70, the tube portions 70C at the bend thereof being provided with a relatively small return bend radius, which e.g. is in the order of a radius to tube diameter ratio of 1 to 2 or the like. With this construction the amount of tube surface laterally exposed to direct impingement of the gases is reduced to a minimum and the possibility of slag build up thereon materially lessened.

As best seen in Figs. 3 and 4 a group 70A of these tubes connects the inlet header 68 with a portion of the intermediate header 69 and a second tube group 70B connects another portion of header 69 to the outlet header 68A. With this construction relatively cool steam delivered by roof tubes 61 by suitable conduits to the inlet header 68 of each platen 67 first flows from the inlet header 68 through tube groups 70A to the intermediate header 69. The steam then flows longitudinally in header 69 and enters tube group 70B from whence it enters outlet header 68A. In the event of any unbalanced steam heating in the radiant superheater platens 67, the flowing of the steam longitudinally within header 69 as it exits from tubes 70A enables some steam mixing to occur therein and the steam discharging therefrom will tend to approach an average temperature.

Serially connected to the radiant superheater section 64 by means of conduits 72 and receiving the steam heated therein is the convection primary superheater section 65 disposed in the main gas pass 51 of the convection section 12. As shown the convection superheater section 65 comprises vertically spaced banks of multiple-loop horizontally disposed tubes. The radiantly heated steam

from the platen section 64 enters inlet header 73, flows through section 65 and discharges therefrom at the outlet header 74, the steam at this point being heated to an intermediate superheat temperature.

Conduits 75 serially connect the outlet header 74 to the secondary inlet header 76 of the secondary superheater 66, the latter consisting of vertical disposed multiple-loop tubes positioned in the gas pass 11 between screens 36 and 62. The steam finally superheated therein is discharged from the outlet header 77 and delivered to a point of use through conduit 78.

According to this invention a radiant reheat 79 is disposed in the upper portion of the furnace between the radiant superheater 64 and screen 36 in a zone where the B.t.u. absorption per lb. of steam flowing therethrough is maintained substantially constant throughout the load range of the unit regardless of the amount of excess air admitted into the furnace. As shown, the radiant reheat comprises serially connected spaced banks 80 and 81 of multiple loop vertically disposed tubes. Each bank includes a plurality of transversely spaced nested tube platens, the platens of bank 80 being spaced on wider centers than those in banks 81, see Fig. 2. Steam to be reheated enters the reheat through an inlet header 82 and is discharged therefrom through header 83.

The economizer section includes serially connected banks 84 and 85 of multiple-loop, horizontally arranged tubes, disposed respectively in the main gas pass and by-pass of the convection section 12.

Since constant steam temperature is the desirable operating datum to be achieved, superheat and reheat control according to this invention is attained by selective firing of burners and by gas bypassing around the convection section 65 of the superheater. The arrangement is such that at full load with maximum gas flow through the unit, the dampers are set so that the gas bypass 52 is handling 20% of the total gas weight flowing through the convection section 12 while at 40% load the bypass 52 is handling approximately 5% of the gas. Thus at low loads the gas mass flow over the convection section 65 is increased and as load is increased the gas mass flow therewith is proportionately decreased. The combination of radiant superheater, which has a "falling characteristic" i.e. steam temperature drops as steam flow increases and convection superheater which has a "rising characteristic" i.e. steam temperature and steam flow increases with increased firing rates when used in conjunction with controlled gas flow over the convection section of the superheater effectively maintains an optimum constant superheat temperature over a widely varying load range.

As the superheater platens 64 project a substantial distance into a relatively high temperature zone of the furnace which may be well above the fusion temperature of the ash in the fuel being burned, slag build on the platens is minimized according to this invention by flowing relative cool steam in that portion of the superheater exposed to the hottest gases and by minimizing the amount of superheating surface extending transversely to the gas flow. Thus as the tube metal temperatures of the platens is maintained relatively cool by the cold steam flowing therethrough, any of the slag particles impinging thereon will tend to become rapidly cooled thereby, causing them to become solidified and thereby rendering the same incapable of sticking to the exposed surfaces of the superheater.

It will be further noted that the steam delivered to the radiant superheater is in a dry state, the vapor dryness resulting by flowing the saturated steam from the steam drum through the "bird cage" which is in heat transfer relationship with the gases flowing through the convection section. Thus, any moisture in the steam is evaporated in the "bird cage" and any residual solids carried thereby deposited in the low temperature gas zone.

While the instant invention has been disclosed with reference to a particular embodiment thereof, it is to be

appreciated that the invention is not to be taken as limited to all of the details thereof as modifications and variations thereof may be made without departing from the spirit or scope of the invention.

What is claimed is:

1. A vapor generating and heating unit comprising enclosing walls defining a setting having a radiant furnace chamber of uniform cross-sectional area and a lateral gas outlet in the upper portion of said setting, a convection section having a lateral gas inlet in the upper portion thereof, a laterally extending gas pass connecting said outlet with said inlet, means dividing said convection section into a main gas pass and a gas by-pass, a vapor drum positioned above said furnace chamber, a plurality of vapor generating tubes disposed in the walls of said furnace chamber and connecting with said drum, means for burning fuel in the lower portion of said furnace chamber resulting in slag forming particles being carried in suspension in a combustion gas flow path having an unobstructed longitudinal flow upwardly through said radiant furnace chamber, said gas thence flowing laterally through said lateral gas pass and downwardly through said connected convection section, damper means for separately proportioning the flow of gas through said main gas pass and by-pass, a plurality of vapor heating tubes disposed in the walls of said convection section, said vapor heating tubes being connected for series vapor flow from said drum, a primary radiant vapor heater connected for series vapor flow from said vapor heating tubes, said primary radiant vapor heater including a plurality of transversely spaced tube platens disposed in the upper portion of said furnace in direct exposure to the radiant heat and slag forming particles in said furnace chamber and unshielded by any furnace structure, each of said tube platens includes a plurality of vapor flow passes, each of said passes being formed of a plurality of independently supported side-by-side U-shaped tubes having closely spaced co-planar inlet and outlet leg portions connected by a return bend, each of said leg portions having an upper portion and a lower portion, said lower portion depending into a zone of said furnace chamber wherein the gases flowing therethrough are at a temperature above the fusion temperature of the gas entrained particles whereby the gas flow over said lower portion is in a direction parallel to the longitudinal axes of said superheated tubes, an inlet header, an outlet header and a mixing header wherein said inlet and outlet leg portions of one vapor pass serially connects the inlet header to said mixing header respectively and said inlet and outlet leg portions of another vapor pass serially connecting said mixing header to said outlet header respectively whereby the tubes of said radiant heater have only a relatively small amount of surface exposed to cross gas flow and slag impingement normal thereto, a primary convection vapor heater connected in series flow with said radiant heater, said primary convection heater being disposed in said main gas pass of said convection section, said dampers being arranged so as to increase the mass gas flow through said main gas pass and over said primary convection heater as load is decreased, a secondary vapor heater connected in series flow from said primary convection heater and disposed in said lateral gas pass and a vapor reheat disposed between said secondary convection-vapor heater and radiant vapor heater.
2. An improved platen type radiant vapor superheater adapted to be directly exposed without shielding to the radiant heat of a furnace chamber fired by a slag forming fuel comprising an inlet header adapted to receive relatively low temperature vapor, an outlet header in alignment with said inlet header, an intermediate mixing header substantially co-extensive and disposed parallel with said aligned inlet and outlet headers, a plurality of radiantly heated vapor flow passes serially connecting said headers for vapor flow therethrough, each of said

passes being adapted to be exposed to heating gases of substantially uniform temperature and including a plurality of depending U-shaped tubes each having closely spaced inlet and outlet leg portions connected at the lower ends thereof by a return bend, said tubes being disposed in side-by-side co-planar relationship to form a tube platen wherein the inlet and outlet leg portions of one pass serially connect the inlet header to the mixing header, respectively, and the inlet and outlet leg portions respectively of another vapor pass serially connect the mixing header to said outlet header, each of said headers having its longitudinal axis lying in a plane parallel to the plane of said tubes.

3. A vapor generator comprising enclosing walls defining a setting having a vertically elongated radiant furnace chamber of uniform cross-section, a liquid-vapor separating drum positioned at the top of said setting, a plurality of vapor generating tubes disposed in the walls of said furnace chamber and connected in communication with said drum, means for burning fuel in the lower portion of said furnace chamber resulting in slag forming particles being carried in suspension in combustion gases whereby said combustion gases have an unobstructed longitudinal flow path upwardly through said radiant furnace chamber, a radiant primary superheater arranged in the upper portion of said setting, said superheater including a plurality of dependently supported U-shaped tubes having an upper portion and a lower portion, said lower portion depending into a zone of said furnace chamber wherein the gases flowing therethrough are at a temperature above fusion temperature of the entrained particles therein, each of said superheater tubes having a downflow leg portion and a closely spaced upflow leg portion connected by a return bend at the lower ends thereof so that the gas flow over the lower portion of said superheater tubes is in a direction substantially parallel to the longitudinal axes of said superheater tubes, and each of said superheater tubes being directly exposed to both the radiation of the flame of said fuel burning means and the combustion gases containing entrained slag forming particles whereby only a minimum amount of the surface area of said lower portion of the superheater tubes is subjected to cross-gas flow thereover, whereby said superheater tubes are unshielded by furnace structure from the effects of slagging and of direct radiation of said flame and combustion gases.

4. A vapor generator comprising enclosing walls defining a setting having a vertically elongated radiant furnace chamber of uniform cross-section, a liquid-vapor separating drum positioned at the top of said setting, a plurality of vapor generating tubes disposed in the walls of said furnace chamber and connecting with said drum, means for burning fuel in the lower portion of said chamber resulting in slag forming particles being carried in suspension in combustion gases whereby said combustion gases have an unobstructed longitudinal flow path upwardly through said radiant furnace chamber, a primary radiant superheater arranged in the upper portion of said setting, said superheater including a plurality of dependently supported U-shaped tubes having an upper portion and a lower portion, said lower portion depending into a zone of said chamber wherein the gases flowing therethrough are at a temperature higher than the fusion temperature of the slag forming particles entrained therein, each of said superheater tubes having a downflow leg portion and a closely spaced upflow leg portion connected by a return bend at the lower ends thereof, said return bend having a radius to tube diameter ratio of substantially 1 to 2, said depending U-shaped tubes being disposed in side-by-side, co-planar relationship so that the gas flow over the lower portion of said superheater tubes is in a direction parallel to the longitudinal axes of said superheater tubes, and each of said superheater tubes being directly exposed to both the radiation of the flame of said fuel burning means and the combustion gases

5 containing the entrained slag forming particles so that only a minimum amount of the surface area of said lower portion of the superheater tubes is subjected to cross-gas flow thereover and to direct impingement of the gas entrained slag forming particles, and whereby none of the radiant heat of said furnace is shielded by furnace structure from acting directly on said exposed tubes.

10 15 20 25 30 35 40 45 50 55 60 65 70 75 8. A vapor generator comprising enclosing walls defining a setting including a vertically elongated radiant furnace chamber of uniform cross-section, a liquid-vapor separating drum positioned at the top of said setting, a plurality of vapor generating tubes disposed in the walls of said furnace chamber and connected in fluid circulation with said drum, means for burning fuel in the lower portion of said chamber resulting in slag forming particles being carried in suspension in combustion gases whereby said combustion gases have an unobstructed longitudinal flow path upwardly through said radiant furnace chamber, a primary radiant superheater arranged in the upper portion of said setting, said superheater including a plurality of dependently supported U-shaped tubes having an upper portion and a lower portion, said lower portion depending into a zone of said chamber wherein the gases flowing therethrough are at a temperature above fusion temperature of the entrained particles therein, each of said superheater tubes having a downflow leg portion and a closely spaced upflow leg portion connected by a return bend at the lower ends thereof, said depending U-shaped tubes being disposed in side-by-side, co-planar relationship so that the gas flow over the lower portion of said superheater tubes is in a direction parallel to the longitudinal axes of said superheater tubes, the upflow leg of one superheater tube being disposed adjacent the downflow leg of the next adjacent superheater tube, and each of said superheater tubes being directly exposed to both the radiation of the flame of said fuel burning means and the combustion gases and to direct impingement of the gas entrained slag forming particles so that only a minimum amount of the surface area of said lower portion of the superheater tubes is subjected to cross-gas flow and to direct impingement of the gas entrained particles thereover whereby said superheater tubes being unshielded by furnace structure from the direct effects of slagging and furnace radiation.

6. A vapor generator having enclosing walls defining a setting including a vertically elongated radiant furnace chamber of uniform cross-section, a liquid-vapor separating drum positioned at the top of said setting, a plurality of vapor generating tubes disposed in the walls of said furnace chamber and connecting with said drum in fluid circulation, means for burning fuel in the lower portion of said furnace chamber resulting in slag forming particles being carried in suspension in a combustion gas whereby said combustion gases have an unobstructed longitudinal flow path upwardly through the furnace chamber, a plurality of radiant primary superheater platen elements transversely spaced in the upper portion of said setting, each of said platen elements including a first and second pass of dependently supported return bend tubes having inlet and outlet leg portions connected by a return bend having a radius to tube diameter ratio of substantially 1 to 2 with said leg portions of each element lying in a common plane, each of said leg portions having an upper portion and a lower portion, said lower portion depending into a zone of said chamber wherein the gases flowing therethrough are at a temperature above the fusion temperature of the entrained particles therein, and said gas flow over the lower portion of said superheater tubes being in a direction parallel with the longitudinal axes of said tubes, each of said superheater tubes being directly exposed to both the radiation of the flame of said fuel burning means and the combustion gases containing the entrained slag forming particles, the arrangement being such that only a minimum amount of the surface area of said lower portion of the superheater tubes is sub-

jected to cross-gas flow and to direct impingement of the gas entrained particles thereover whereby said exposed surface area of said tubes is unshielded by furnace structure from the direct radiation effects of said flame and combustion gases, a common mixing header serially connecting the outlet leg portion of said first tube pass with the inlet leg portion of said second tube pass whereby any unbalanced heating of the vapor flowing in said first tube pass tends to be averaged out in said mixing header to thereby minimize any unbalanced heating occurring in said second tube pass, said header having its longitudinal axis extending in a plane parallel to the platen of said tubes whereby the relative position of said primary radiant superheater tubes to said gas flow and to the vapor flow therein cooperate to maintain said primary superheater substantially free of external slag accumulations while maintaining the tube temperatures of said radiant heater within tolerable temperature limits.

7. A vapor generator having a front, rear and connecting side walls defining a setting including a vertically elongated radiant furnace chamber of uniform cross-section, a liquid-vapor separating drum positioned at the top of said setting, a plurality of vapor generating tubes disposed in the walls of said furnace chamber and connected in fluid circulation with said drum, means for burning fuel in the lower portion of said furnace chamber resulting in slag forming particles being carried in suspension in combustion gases wherein said combustion gases have an unobstructed longitudinal flow path upwardly through said furnace chamber, a radiant primary superheater comprising a plurality of platen elements spaced transversely in the upper portion of said setting, each platen element including an inlet header for receiving relatively low temperature vapor, an outlet header in alignment with said inlet header, an intermediate mixing header substantially co-extensive with and disposed parallel to said aligned inlet and outlet headers, and a plurality of radiantly heated vapor flow passes serially connecting said headers for vapor flow therethrough, each of said passes including a plurality of dependently supported return bend tubes having an inlet and outlet leg portion connected by a return bend having a radius to tube diameter ratio of substantially 1 to 2 with said leg portions lying in a common plane, each of said leg portions having an upper
